MINING MACHINE.

No. 568,937.

Patented Oct. 6, 1896.

UNITED STATES PATENT OFFICE.

HENRY H. BLISS, OF WASHINGTON, DISTRICT OF COLUMBIA.

MINING-MACHINE.

SPECIFICATION forming part of Letters Patent No. 568,937, dated October 6, 1896.

Application filed July 27, 1891. Serial No. 400,893. (No model.)

To all whom it may concern:

Be it known that I, HENRY H. BLISS, a citizen of the United States, residing at Washington, in the District of Columbia, have invented certain new and useful Improvements in Mining-Machines, of which the following is a specification, reference being had therein to the accompanying drawings.

Figure 1 is a top plan view of a part of a mining-machine embodying my improvements. Fig. 2 is a side view. Fig. 3 is a rear view. Fig. 4 is a longitudinal section of the frame. Fig. 5 is a partial section, enlarged, on the line $x x$, Fig. 1. Fig. 6 shows a modified form of drill-support. Figs. 7 and 8 show comparatively the different action of the machines heretofore in use and of that herein. Fig. 9 is a cross-section on the line $x' x'$ of Fig. 1. Fig. 10 is a partial plan view. Figs. 11 and 12 are a plan and a side elevation of a modified form of carriage-moving mechanism.

This invention relates to improvements in mining-machines of the sort wherein use is made of a chain for both actuating and carrying the cutters.

One of the objects is to provide means for clearing a path for the cutter-chain at the sides of the machine.

Another object is to provide an improved arrangement of the cutter-chain and the supporting-frame whereby it shall be held properly with respect to the carriage, the bed, and the material being cut.

Another object is to provide a chain cutting mining-machine having a bed-frame and a carriage comprising a sliding thrusting-frame which supports the chain directly in the planes of the thrusting-frame and parallel to the bed but relatively remote therefrom, with devices for holding the chain-frame in proper lines.

In order to support the cutting apparatus and the driving mechanism, any suitable carriage or bed or main frame can be employed. As shown, a bed is provided consisting of side bars A A, connected by cross-bars a and supported upon shoes A'. Upon this bed a carriage is mounted having a rear part B and forwardly-extending bars B'. The bars B' constitute the main longitudinal part of the chain-frame and are fitted in guides at A²,

supported by the bed or main frame, and at the rear are secured to the rear part B, which latter comprises a plate or platform fitted in guides on the longitudinal bed-bars A and having projecting parts for supporting the motor, together with the driven shaft and gearing.

The cutting apparatus comprises a drill or drills C and a chain D, provided with cutters d. The drill-stems c are mounted in hangers or carriers E at the rear and E' at the front ends. The bits or cutters of the drills may be of any suitable sort. They are rotated by suitable gearing, that shown comprising worm-wheels F and worms g on the main driving-shaft G. The chain D, provided, as aforesaid, with cutters d, is so arranged as to have the active ends of the cutters pass beneath and out from under the coal on the longitudinal lines of the apertures formed by the drills, so that there shall be no resistance to the said cutters either when entering or coming out, and so that the cutters shall be permitted to take their work squarely.

The chain D is carried by two front wheels D' D² and is driven by a rear wheel D³, there being in Fig. 1 idlers or wheels at D⁴ D⁴. The wheels D' D² are carried by the bars B' B' of the sliding frame either directly or by means of one or more cross-bars H H'.

The cross-bars H H' may be integral with the drill-brackets E' E', or the latter may be formed separately and adapted to carry both the drills and the chain-wheels, (see Fig. 5,) in which case they will be bolted or otherwise firmly fastened to the cross-bars H H'; or the brackets for the drills may be formed separately from the support of the chain-wheels, as is shown in Fig. 6.

The shaft G is driven by a motor I through a train of suitable gearing i i'. It carries the worm g', engaging with a wheel K on a shaft k. This shaft carries the chain-driving wheel D³.

Of course any suitable motor can be used; but I have found that an arrangement thereof and of the power-transmitting shafting and gearing substantially such as shown is very advantageous. Generally in chain cutting mining-machines the power has been generated or applied on longitudinal lines at the center of the machine in such way as to necessitate

the use of numerous wheels and more or less complicated shafting and gearing. It is well known to be desirable to use, as largely as possible, straight spur-gearing in machines of this character, because of the economy of the power, particularly for taking the power from the motor to the shafting which distributes it to the different operating parts.

In the present machine the armature-shaft 10 is placed transversely and connected by straight gear with the main cross power-transmitting shaft G, which, in turn, is geared directly to the chain-driving shaft and to the carriage-moving mechanism. In this way 15 there can be the fullest economy of power.

I have not shown all of the details of the standards or brackets for mounting the various shafts and wheels, as in that respect 20 preference or circumstances can be followed at will.

It will be seen that a relatively large driving-pinion is indicated on the armature-shaft, by which ample speed is insured for the worm-gearing that drives the chain-actuating shaft k, but of course with respect to 25 such matters as speed, the ratios, and kinds of gearing preference can be exercised and modifications made without departing from the essential features of arrangement and 30 construction of the parts.

It will be seen that when the motor or engine is in motion the shaft G will cause the rotation of the drill-stems C C, together with the drills, and at the same time, through the 35 wheels K and D³, will drive the chain D so as to compel its cutters to travel in the direction of the arrow, Fig. 1, and they will remove the material lying between the drill-apertures. At the same time the carriage is advanced. 40 This is done in any suitable way. I have shown a rope and drum, the former being indicated by L and the latter by L'. The rope is secured to the bed-frame, and the drum is mounted upon the carriage. It is rotated by 45 a worm M on shaft G, which worm drives worm-wheel M' on shaft m. At the lower end of the shaft there is a worm m', which, meshes with the worm-wheel N on the drum. The relative speeds of the parts mentioned 50 should be such as to cause the carriage to advance slowly while the cutting is being effected.

The carriage can be withdrawn in any suitable way. There are numerous old and well-known devices for advancing and withdrawing the carriages of these machines, any preferred form of which can be used. In Figs. 55 10 and 11 there is shown one form. In this the carriage-advancing drum L' is loose upon 60 a shaft l, and upon the same shaft there is another drum L² and a clutch L³, which is splined to the shaft. A rope or cable L⁴ is secured to the drum L² and also to the rear part of the frame. After the carriage has 65 been moved forward the clutch L³ is moved into engagement with the drum L², and as the rope is carried from this drum in a way op-

posite to that in which the advancing rope L is taken from its drum the continuous rotation of the shaft l will cause the pulling back 70 of the carriage. The drum L² is made of a diameter larger than that of the drum L', the dimensions in these respects being such as to produce the desired differences in speeds—that is to say, the carriage generally should 75 go forward with a relatively slow speed, while for the sake of economy it should be brought back with a considerably higher speed. At the same time it is not desirable to reverse any of the rapidly-driven parts of the machine. The present construction of carriage-moving apparatus meets both of these ends, as it is merely necessary to move the clutch from one drum to the other to reverse the motion of the carriage, and as the diameter of 80 the pulling-back drum is larger than that of the feed-drum the speed will be correspondingly greater during the backward movement.

By employing a single drill at one end of the cut all the desired purposes can be reached. 90 A passage-way is formed by it for the forward-moving part of the cutter-chain, and the backward-moving part of the chain has a passage-way provided in the previous cut, so that the cutters when in engagement with the coal are 95 delivered to and removed from their work in the way shown in Fig. 8. A comparison of Figs. 7 and 8 will disclose the great advantage incident to having perfectly free passage-ways for the chain cutters at all times other 100 than when they are traversing the line of cut. In using chain cutting-machines as heretofore constructed serious trouble and loss of power have been experienced from the fact that there is more or less engagement of the cutters with the coal both as they are just reaching the line of movement across the face and when they are moving backward therefrom. The chains, as is well known, necessarily become slack after being used, and then when 105 subjected to strain in operation they tend to be displaced from their carrying-wheels. By providing an unobstructed pathway for them when moving inward and moving outward from their line of operation their action can 110 be made much more uniform on the operative line, they can be held more firmly in place upon the supporting-wheels, and the cutters 115 can be held squarely to their work.

The drill or drills act to prevent side thrust, 120 that is, obviate any lateral reactionary movement of the bed or carriage because of the engagement of the chain cutters with the coal. Machines have been heretofore constructed having cutter-chains and drills arranged on a horizontal line near the central vertical plane of the machine and above the central part of the chain. It is to obviate 125 the difficulties and loss incident to machines of that sort that the present form has been 130 provided. The last-described drill arranged centrally of the machine has been employed for the purpose of steadyng the machine and preventing side thrust. By using it a large

aperture is bored in the coal, which not only consumes power, but causes a waste of the material. In my case the aperture that is thus formed is so arranged as to form part of the necessary undercut—that is to say, the kerf formed by the chains is horizontal in the same plane as the aperture formed by the drill or drills; and therefore, in addition to providing an unobstructed passage-way for the chain-cutters and in addition to overcoming the lateral reactionary thrust, the drills are utilized to shorten up the amount of cut that is required of the chain.

I am aware of the fact that it has been heretofore proposed to use a machine having at the front end of the carriage a transverse reciprocating saw or cutter and longitudinally arranged drills at the ends of the saw; but several serious difficulties have been experienced in attempting to use machines of the sort referred to. As the saw moves back and forth it tends to carry the cuttings away from the paths of exit as much as it tends to carry them toward said paths. The cutter-bar or saw-shank itself blocks or fills up the pathway directly behind the cutters, so that the cuttings or slack is compelled to move laterally until it reaches the drill-apertures. This, in practice, it has been found exceedingly difficult to attain. Another style of machine has been also proposed similar to that last described, except that the reciprocating saw was duplicated, the upper moving to the right while the lower moves to the left, and there being a vertical space provided between them, through which space the cuttings could be drawn backward.

I obviate all trouble of blocking or choking the machines by the cuttings by having the chains arranged in such way that the cuttings will be carried out continually in one direction.

I prefer to have the dimensions of the drill-aperture and of the slot formed by the chain-cutters proportioned to each other substantially as shown in Fig. 6. This enables me to give a strong support to the drill at the front or working end, also to carry the cutters forward through the drill bracket or support, and to have the cutters so related in dimension to the vertical dimensions of the parts which support the chain that said cutters shall open up a kerf large enough to permit the said supporting parts to move freely under the coal. The bracket E' has a bearing part e' for the drill, an upper arm e' , and a lower part e^2 . One of these carrying-arms can be dispensed with when the dimensions of the cut are such that sufficient metal can be interposed between the drill and the carriage to carry the former sufficiently firmly.

To assist in preventing the operative parts of the drill from experiencing any side or lateral reactionary thrust as a result of the action of the chain cutters d , I employ a shoe or bearing-piece R at or near the drill-head, which receives any pressure from the chain

cutters and relieves the drill. It may be secured to the carriage in any preferred manner, and travels therewith in such way as to bear against the vertical wall of the coal. As shown, it projects laterally from the carrier D' . Its wall engaging or bearing surface is preferably rounded.

By examining Fig. 5 it will be seen that the aperture cut by the drill is considerably larger than this steadyng piece or projection, the latter projecting laterally. A holder of this sort is superior to one of the sort heretofore used, consisting of a drill-bracket of the same diameter as the aperture cut by the drill. Mine extends out in one direction only—that is, to the outer side of the circle of the cut, there being around the greater part of such circle nothing to contact with the wall of the bore.

By an examination of the drawings it will be seen that the machine here shown differs materially, in several respects, from the earlier ones having chain cutters. The chain travels in a plane always parallel to the pathway or guide on the bed which is followed by the motor-support or rear part of the carriage.

Objections are incident to those machines which have the rear chain-driving wheel in one horizontal plane (relative to the bed-guide) and the front wheels in another plane. In such cases the plane of the chain is inclined downward from the rear to the front in relation to the planes of travel of the carriage, due to the fact that the chain-driving wheel has to be somewhat higher than the front wheels in order to have the chain cross over the carriage-bars and the bed-bars. The consequence is that the chain does not cut squarely across the lines of travel as it advances bodily, but the cutters are dragged on the top and bottom of the kerf, necessitating a different arrangement and adjustment of the upper and lower cutters, and even with such adjustment there results an unevenness of action in the two sets of cutters.

The only way heretofore suggested for arranging the cutter-chain parallel to the bed-frame has been to bend the carriage-bars downward at the rear and place the chain, the front cross-head, the front wheels, and the side idler sprockets or guides in planes above and eccentric to the planes of the thrusting-bars of the carriage-frame. The result of this is to have all of the powerful strain of the machine on lines where it cannot be resisted by the thrusting-bars, but, on the contrary, the latter are bent or "buckled" up by the eccentric draft. To avoid these difficulties, I first place the chain and its special frame in a plane relatively remote from but parallel to the plane of the bed-guides. Then I mount the sliding guide-bars B' , the cross-bar H , the front chain-wheels, the rear driving-wheel, and the chain itself all substantially concentric as to the central plane of travel of the chain-links, which plane is parallel to that of the guide on the bed-bars,

which controls the path of the cutting apparatus as a whole.

It will be seen that there is a relatively large open space horizontally between the edges of the chain cutters and the bed-bars, (see Fig. 2,) so that these can be moved very rapidly across the lines of the bed-bars without any danger of striking or interfering with them, this free space resulting from the presence of vertically-extended supports, as at A², which support the chain-frame in a position relatively remote from the bed-bars and yet hold said frame parallel to the bed-guide. Then to avoid the weakening of the framework of the machine, which might result from thus placing the chain-frame and the bed-bars A in horizontal planes relatively remote from each other, (which weakness would be felt by the bars B' and their front support and guide,) I employ a bracing and holding projection, as at R, secured to and traveling with the carriage-frame and bearing against the vertical wall of the coal, it relieving the chain-frame of the lateral twist or torsion which it would otherwise experience by being disposed in a plane more or less distant from the planes of the bed-bars A.

I am aware of the fact that machines heretofore made have had a relatively small chain-30 driving wheel, as at D³, together with wheels or supporting-guides, as at D⁴, and the chain being supported so as to travel in straight lines diverging outward from the central lines of the machine; but I believe myself to be the first to have devised a machine of this sort wherein a relatively small and correspondingly powerful drive-wheel, as at D³, could be employed, together with a front chain-support 35 extended laterally (as from wheel D' to wheel D²) and wider than the bed, with a chain diverging from the drive-wheel D³ outward on straight lines, and with thrusting and carrying bars, as at B', in the central lines of thrust 40 of the chain and have all of these parts arranged, as aforesaid, in the same plane, which plane is parallel to the bed-guide.

I am also aware of the fact that chain cutter-machines have been made with various forms of legs, rollers, or ground supports. 50 The present construction is of the class in which use is made of runners or shoes at A', by which the machine can be readily slipped forward or back when it is to be bodily moved, as it has to be every few minutes. 55 There is serious disadvantage incident to these chain cutter-machines which have legs or shoes separated from each other, some at the front and some at the rear. The chains extend over so much space that their cutters 60 are a serious obstruction in transporting the machine or adjusting it on the ground and frequently are the cause of accidents. When the bed is placed on such longitudinal runners as those at A', it can be readily slipped 65 over the ground by the application of bars at the ends.

What I claim is—

1. The combination of the carriage, the drill, and the chain carrying cutters, arranged to move forward longitudinally in the aperture formed by the drill, and then transversely at an angle to said aperture, substantially as set forth. 70

2. The combination with the carriage, of the drill, the bearing for the said drill, and the chain provided with cutters and arranged to travel first longitudinally of the machine and then transversely in the plane of the drill-apertures, substantially as set forth. 75

3. The combination with the carriage, of the drill, the chain provided with cutters moving continuously in one direction in the plane of the drill and mounted independently thereof, and the drill bracket or support extending across the vertical planes of the path 85 of the chain cutters, substantially as set forth.

4. The combination with the carriage, of the drill, the chain provided with cutters moving transversely in the plane of the drill, forward from a wheel on the rear of the carriage across the front of the carriage and then to the rear thereof, and the drill support or bracket arranged to move partly in the aperture formed by the drill and partly 90 in the kerf formed by the chain cutters, substantially as set forth. 95

5. The combination of the carriage, the drill, the chain having cutters moving transversely in the plane of the drill, and the shoe or traveling abutment, as at R, substantially 100 as set forth.

6. The combination of the bed, the carriage, the chain provided with cutters and moving transversely across the front end of the carriage, and a holding projection secured 105 to the carriage and extending outward in the horizontal planes of the chain and engaging with the wall of the coal to provide the carriage with an abutment against lateral movement, substantially as set forth. 110

7. The combination of the bed, the carriage, the single cutter-chain moving transversely across the front end of the carriage, the devices for advancing and withdrawing the carriage on the bed, and a projection 115 mounted stationarily on the front end of the carriage and engaging the side wall of the main kerf, whereby said projection forms an abutment for the carriage against the lateral thrust of the cutters, substantially as set 120 forth.

8. The combination with the carriage, of the drill, the chain having cutters moving transversely of the machine in the planes of the drill, and the arms or brackets for carrying the drill having inner ends of a vertical dimension less than the kerf formed by the chain cutters and having passages for the said 125 chain cutters, substantially as set forth.

9. The combination of the carriage, the 130 chain having cutters which move transversely across the path of the carriage, and a cutting mechanism at the end of the path of the operative part of the chain, arranged in advance

of the cutters at the said end of said path, said cutter-chain and said cutting mechanism lying in the same horizontal planes whereby the chain cutter operates in transverse lines 5 only, substantially as set forth.

10. The combination of the carriage, the chain having cutters moving transversely of the carriage and the drill forming an aperture of a vertical dimension greater than that of 10 the kerf formed by the chain cutters, and the drill support or bracket having a part wider vertically, and a part narrower vertically than the kerf of the chain cutters, substantially as set forth.

15. 11. The combination with the bed having channel-bars, front carriage-guides located in horizontal planes other than those of the channel-bars, and the front chain-guide wheels, of a rear chain-driving wheel, a cutter-chain 20 traveling on lines diverging from said wheel and subsequently around front guide-wheels, and a carriage across the front end of which said chain travels on said guide-wheels, said carriage having a rear portion sliding in said 25 channel-bars of the bed, and also having one or more longitudinal sliding guide-bars lying in the horizontal planes of the chain, and sliding in said front guides on the bed, all of said parts being arranged substantially as described 30 whereby powerful leverage can be imparted through a relatively small driving sprocket-wheel, and the planes of travel of the chain and the carriage can all be maintained parallel to the horizontal planes of the kerf, 35 substantially as set forth.

12. The combination with the bed having side bars, and cross-braces connecting said side bars, and a carriage mounted on said bed, having a chain guiding and supporting 40 frame, an endless cutter-chain passing entirely around the said chain-guiding frame in a path extending from a relatively small main driving-wheel on lines diverging outwardly from the said driving-wheel for guiding the 45 chain across the front, said chain supporting and guiding frame, said driving-wheel, said loose wheels, and said chain all being arranged in the same substantially horizontal planes, other than the horizontal planes of the bed-bars, 50 substantially as set forth.

13. In a mining-machine, the combination, of the bed, the carriage traveling thereon, an endless chain passing from the rear of the carriage across the front thereof, and a steady- 55 ing projection secured to the front end of the carriage and extending laterally to the side wall of the main kerf, and having a wall engaging or bearing face lying entirely between the upper and the lower horizontal planes of 60 the chain cutters, substantially as set forth.

14. In a mining-machine, the combination, of the bed having side bars with longitudinal guides, the motor-carriage fitted to the said guides, a cutter-chain arranged and traveling 65 in a plane substantially parallel to the plane of the said guides, a chain-frame having one or more longitudinal thrusting and carrying

bars in the plane of the chain-links and a front cross-support H extended beyond the side lines of the bed, front chain-wheels on 70 said cross-support in the horizontal planes of the thrusting-bars, a rear chain-driving wheel, and a chain support or guide between the said driving-wheel and the front wheels, said guide being arranged in the plane of the 75 thrusting-bars to support the chain vertically and hold it on lines which diverge outwardly from the driving-wheel, all of the last-said parts (to wit, the chain-frame, the front cross-support, the front wheels, the driving-wheel, 80 and the intermediate chain-guide) being arranged in substantially the same plane and parallel to the guide on the bed, substantially as set forth.

15. In a mining-machine, the combination 85 of the following elements, namely, the portable bed having longitudinally-arranged side bars, longitudinally-arranged shoes or runner-supports below said side bars, a carriage having a motor-support fitted in a guide on 90 the said bars of the bed, a chain-frame having one or more longitudinal thrusting and carrying bars, a cutter-chain arranged in the horizontal planes of the thrusting-bars, and parallel to the plane of the bed-bars, front 95 wheels for said chain, a power-wheel for said chain on the motor-support (all the said wheels being in a plane substantially parallel to the said bed-guide), the front stationary guide for the chain-frame, and a traveling 100 holder on the carriage bearing against a wall cut in the coal, whereby the cutters can while cutting be advanced on straight lines without interference with the bed or longitudinal runners, substantially as described. 105

16. In a mining-machine, the combination 110 of the following elements, namely, a portable bed-frame, longitudinally-arranged runners or shoes below the bed-frame, a motor-support fitted to and guided on the bed in a fixed 115 path, a chain-frame having one or more longitudinal thrusting and carrying bars, a cutter-chain arranged thereon to travel in planes substantially coincident with those of the thrusting-bars and parallel to said bed-guide, 120 a front guide for said thrusting-bars in the plane of the chain-links and held by a support extending vertically away from the plane of the guide on the bed to the plane of the chain, and a rear traveling support for the 125 chain-frame extending vertically to the planes of the cutter-chain, whereby the chain-frame is held in the plane of the chain and out of contact with the bed-bars to provide free space for the cutters to travel without interference from the bed or runners, substantially as set forth.

17. In a mining-machine, the combination 130 of the following elements, namely, a portable bed having longitudinally-arranged side bars providing a carriage-guideway, longitudinal runners or supports under the bed, a motor-support fitted to the guideway on the bed, a cutter-chain, a chain-frame having one or

- more longitudinal bars B' in the plane of the chain, a front guide on the bed fitted to the said bars B', a cross-support H at the front of said bars, a chain-driving wheel, the last-said parts (to wit, the driving-wheel, the chain, the sliding bars B', and front cross-support H) being held substantially parallel to the aforesaid bed-guides, whereby they can be advanced and retracted without interfering with the bed or ground support, and a steadyng-holder traveling with the carriage and bearing against a wall of the coal to prevent torsion of the chain-frame and hold it in line, substantially as set forth.
18. The combination of the bed, the carriage, the cutter-carrying chain, the rear horizontal driving sprocket-wheel, the vertical shaft secured to said sprocket-wheel, the carriage-moving mechanism having a rotary member secured to and mounted on the carriage on a transverse axis immediately behind the vertical chain-driving shaft, and a relatively stationary member secured to the bed and engaging with the rotary member,
- 25 the electric motor mounted on and traveling with the carriage in fixed relations to the rotary member of the carriage-moving mechanism and to the cutters, the chain-driving gearing actuated by the electric motor, and the worm and worm-gearing interposed between the chain-driving gearing and the carriage-moving mechanism, substantially as set forth.
19. The combination of the bed, the carriage, the cutter-carrying chain, the horizontal chain-driving sprocket-wheel, the vertical shaft carrying said sprocket-wheel, the carriage-moving mechanism having a rotating member mounted on the carriage on a transverse axis, and a stationary member secured to the bed and engaging with the rotary member, the electric motor secured directly to the carriage and moving therewith in fixed relation to the cutters and the carriage-moving mechanism, said motor being connected to the said chain-driving shaft, and the longitudinally-arranged shaft connecting the chain-driving mechanism with the transverse carriage-moving mechanism, substantially as set forth.
20. The combination of the bed, the carriage, the cutter-carrying chain, the horizontal driving sprocket-wheel, the vertical shaft carrying said wheel, the electric motor secured to the carriage, the transversely-mounted rotating carriage-moving mechanism below the motor, the power-gearing situated on the carriage in front of the motor for actuating both the vertical chain-shaft and the carriage-moving mechanism, substantially as set forth.
21. The combination of the bed, the carriage, the chain provided with cutters, the horizontal driving sprocket-wheel, the vertical shaft carrying said wheel, the shaft and gearing in front of said vertical shaft and connected thereto, the carriage-moving mechanism having a rotary member mounted on the carriage behind the vertical shaft, and the

intermediate longitudinally-arranged shaft for driving the carriage-moving mechanism and extending therefrom to the aforesaid shaft and gearing in front of the vertical chain-driving shaft, substantially as set forth.

22. The combination of the bed, the carriage, the cutter-carrying chain, the horizontal driving sprocket-wheel therefor, the vertical shaft carrying said sprocket-wheel, the motor, the power-shaft and gearing in front of the motor and connected to the vertical chain-shaft, a rotating carriage-moving mechanism mounted transversely on the carriage behind the vertical chain-shaft, and the longitudinally-arranged power-shaft connected to the said carriage-moving mechanism and extending forward to the aforesaid shaft and gearing in front of the motor, substantially as set forth.

23. The combination of the bed, the carriage, the cutter-carrying chain, the horizontal driving sprocket-wheel therefor, the vertical shaft carrying said sprocket-wheel, the motor on the carriage, the transversely-mounted rotary carriage-moving mechanism on the carriage behind the vertical chain-shaft, the gearing in front of both the motor and the vertical shaft for driving the chain, and a shaft extending backward from said front gearing and under the motor, and connected to the carriage-moving mechanism, substantially as set forth.

24. The combination of the bed, the carriage, the cutter-carrying chain, the horizontal driving sprocket-wheel therefor, the chain-driving mechanism having a vertical shaft for said sprocket-wheel and a horizontal power-shaft geared to the vertical shaft, the carriage-moving mechanism having a rotary member mounted transversely on the carriage behind the vertical shaft, and the power-shaft driven by the said chain-driving mechanism and connected to the said rotary carriage-moving member, substantially as set forth.

25. The combination of the bed, the carriage, the cutter-carrying chain, the horizontal driving sprocket-wheel therefor, the vertical shaft for said wheel, the transverse power-shaft geared directly to the vertical chain-shaft, the electric motor having a transversely-mounted armature-shaft, the gearing connecting the armature-shaft and said power-shaft, a carriage-moving mechanism also mounted transversely on the carriage, and a longitudinal shaft between the carriage-moving mechanism and the transverse power-shaft, substantially as set forth.

26. The combination of the bed, the carriage, the cutter-carrying chain, the horizontal sprocket-wheel for said chain, the vertical shaft carrying said wheel, the electric motor with the transversely-mounted armature, the transverse power-shaft interposed between the motor and the vertical shaft, and the straight spur-gearing at the side of the motor in the longitudinal planes of the

machine and interposed between the armature and the transverse power-shaft, substantially as set forth.

27. The combination of the bed, the carriage, the horizontally - arranged endless chain, the frame for the said chain, the rear driving sprocket-wheel, the vertical shaft carrying said sprocket-wheel, the horizontally-arranged power-shaft geared to the vertical shaft, the carriage-moving mechanism on the carriage, the longitudinally-arranged intermediate shaft geared to the said power-shaft and to the carriage-moving mechanism, the electric motor secured to the carriage and having a transversely - mounted armature-shaft, and the straight spur-gearing at the side of the machine in planes parallel to the vertical longitudinal planes thereof and connecting the armature-shaft with the transverse power-shaft, substantially as set forth.

28. The combination in a mining-machine,

of the bed, the carriage moving in a guide thereon, a chain, provided with cutters, mounted on said carriage and moving in one direction across the front end of the carriage, 25 a drill arranged to bore an aperture additional to the kerf formed by the chain, and a steadyng or holding projection situated eccentrically as to the axis of the drill and extending laterally to the outer circle of rotation of the cutter on the drill, said bearing projection and its support being smaller in cross-section than said bore, whereby friction is reduced, and a space for clearance is provided, as set forth. 30 35

In testimony whereof I affix my signature in presence of two witnesses.

HENRY H. BLISS.
